SUCTION CLEANER POLISHER ATTACHMENT

Eugene F. Martinec, East Cleveland, Ohio, assignor to Health-Mor, Inc., Chicago, Ill., a corporation of Illinois

Application March 21, 1955, Serial No. 35,138

Term of patent 14 years

(Cl. D9—2)

Fig. 1

Fig. 2

Fig. 3

Fig. 5

Fig. 1 is a perspective view of a suction cleaner polisher attachment showing my new design;

Figs. 2, 3, 4, and 5 are front elevational, plan, side elevational, and rear views, respectively, on a reduced scale of the polisher attachment shown in Fig. 1.

I claim:

The ornamental design for a suction cleaner polisher attachment, substantially as shown.
